(57) **CLAIM**

The ornamental design for a vehicle exterior body, toy replica and/or other replica, as shown and described.

DESCRIPTION

FIG. 1 is a front elevational view of a vehicle exterior body, toy replica and/or other replica, showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a top, front, and left side perspective view thereof; and,

FIG. 7 is a top, rear, and left side perspective view thereof. The portions of the vehicle body shown throughout the drawing views in de-emphasized and half-tone portions outside the broken lines and the broken lines representing the boundary and configuration of what is claimed as the design are for illustrative purposes and environmental purposes and form no part of the claimed design.
